AUTOMATIC TRANSMISSION TEST UNIT

John J. Marick, Stamford, and Sidney Gerhard, Norwalk, Conn., assignors to Consolidated Diesel Electric Corporation, Stamford, Conn., a corporation of New York

Filed July 20, 1959, Ser. No. 56,837

Term of patent 14 years

(Cl. D52—1)

Fig. 1.

Fig. 2.

Fig. 3.

Fig. 4.

Fig. 5.

Fig. 1 is a front elevational view of an automatic transmission test unit showing our new design;

Fig. 2 is a rear elevational view;

Fig. 3 is a top plan view;

Fig. 4 is a left end view of that shown in Fig. 1; and Fig. 5 is a right end view of that shown in Fig. 1.

We claim:

The ornamental design for an automatic transmission test unit, substantially as shown.
